(57) **CLAIM**

The ornamental design for a telecommunications speakerphone, as shown and described.

DESCRIPTION

FIG. 1 is front view of a telecommunications speakerphone showing the design;

FIG. 2 is front-left perspective view thereof;

FIG. 3 is a left perspective view thereof;

FIG. 4 is a bottom-left perspective view thereof; and,

FIG. 5 is a right perspective view thereof with the optional clip shown as environment.

The broken lines encompassing unshaded regions represent the bounds of the claimed design while all other broken lines are directed to environment and are for illustrative purposes only; the broken lines form no part of the claimed design.
